(57) **CLAIM**

The ornamental design for an excavator body exterior, as shown and described.

DESCRIPTION

FIG. 1 is a perspective view of the excavator body exterior showing our new design;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken lines shown in the drawings are included for purposes of illustrating portions of the excavator, excavator body, and excavator cab and form no part of the claimed design.
